UNITED STATES PATENT OFFICE.

OLFORD FRANK RUSE, OF UNIONTOWN, PENNSYLVANIA.

RAILROAD TIE.

Application filed July 29, 1924. Serial No. 728,934.

To all whom it may concern:

Be it known that I, OLFORD FRANK RUSE, a citizen of the United States, residing at Uniontown, in the county of Fayette, and

5 Commonwealth of Pennsylvania, have invented certain new and useful Improvements in Railroad Ties, of which the following is a specification, reference being had therein to the accompanying drawings.

10 This invention relates to a rail-tie that includes metallic elements, cushioning elements, and a body of concrete or other suitable material cast or molded while in a plastic condition.

15 It is an object of the invention to provide a tie of that type having its body reinforced in such manner that it will retain its integrity under stresses and strains imposed thereon in service.

20 Another object of the invention is so to arrange the parts of the structure that much of the stresses and strains imposed thereon by the passage of rolling stock over rails supported thereby is taken by a member therein, not embedded in the plastic structure.

25 It also is an object of the invention to embody in such a tie means whereby track-rails may be associated securely and removably therewith and reliably held thereon in proper relative positions.

30 Still another object of the invention is so to associate cushioning elements with the tie that they will sustain weight, torsional, and other stresses imposed by the rails in various directions.

35 When considered in connection with the description herein, the characteristics of the invention are apparent from the accompanying drawings, forming part hereof, wherein an embodiment of the invention is disclosed, for purposes of illustration.

40 Although the disclosures herein exemplify what now is considered to be a preferable embodiment of the invention, it is to be understood that it is not the intention to be limited necessarily thereto, in interpretation of the claims, as modifications and adaptations within the limits of the claims can be made without departing from the nature of the invention.

45 Like reference-characters refer to corresponding parts in the views of the drawings, of which—

50 Fig. 1 is a plan view;

Fig. 2 is a side elevation;

Fig. 3 is a view of the spreader;

Fig. 4 is a section on the line 4—4, Fig. 1;

Fig. 5 is a section on the line 5—5, Fig. 1; and

Fig. 6 is a view of the horse.

In the drawings, A designates track-rails.

The tie includes a body 7 of concrete or other suitable, initially plastic, material cast or molded and reinforced by metallic rods or bars 8, 9, and 10 extending longitudinally thereof. The body has thickened end portions 11, and an intermediate connecting portion 12 of less thickness in the vertical direction, and it has an opening or chamber 13 extending its entire length in substantially central disposition for a purpose hereinafter explained.

75 For the purpose of affording bearings for track-rails associated with the tie, for sustaining the stresses and efforts imposed on the tie by the rails during passage of rolling stock thereover, and as instrumentalities employed in connecting the rails to the tie, two metallic members 14 are disposed longitudinally and are embedded in the tie, one in each end portion.

80 Each of these members 14 is a substantial, 85 rectangular casing of a length sufficient to be disposed under a rail and under elements employed to clamp the rail on the tie, and for convenience it hereinafter is referred to as a "horse." It may be made 90 economically of sheet metal of suitable thickness and strength, as, for example, of steel boiler-plate bent to shape and welded at its abutting edges along the line 15. Its sides and bottom are formed with openings 95 16 to facilitate its bondage in the plastic body. A plate 17 extends longitudinally inside of and between the top and bottom of each horse, to the sides of which it is secured by having depending side flanges 100 18 welded or riveted thereto.

105 The horses are positioned in such manner in the tie-body during the molding or casting thereof that their flat tops are flush with the top of the body and the bottoms of the plates 17 are substantially flush with the top of the chamber 13. The body material fills the space in the horses above the plates 17, and also the space below those plates, except that occupied by the chamber 110 13. Two openings 19, one on each side of the rail, extend downwardly through the

top and plate of each horse and through the body material therebetween to the chamber 13. Upper reinforcing members 8, one on each side of the openings 19, extend through 5 the horses and contact with the tops of the plates 17, the horses rest on the lower reinforcing members 9, and the intermediate reinforcing members 10 contact with the sides of the horses. Because of the association of the reinforcing members with the horses in this manner, stresses and efforts imposed upon the horses in various directions by the rails are resisted by those members, the horses are held reliably in the 10 body, and the integrity of the structure is maintained.

A cushioning element 20, of wood or other more or less yielding substance rests on the top of each horse; a metallic plate 21 rests 20 on the cushioning element; a rail A rests on the plate; and the rail is secured in place on the rail by clamp members 22.

The clamp members are held down on the plate by engagement therewith of heads 23 25 of bolts 24 having screw-threaded lower end portions 25. The threaded portions of the bolts engage in threaded openings 26 in an elongated spreader member 27 positioned in the chamber 13, and that member is free 30 of other connection with parts of the tie. The spreader preferably is formed of sheet steel having its terminal portions bent back against its body to afford strengthening laps 28 of substantially the length of the horses 35 and through which the threaded openings 26 extend. The spreader and the threaded openings therein are coordinated with the bolts in such manner that its lapped end portions are disposed in the horses under 40 the plates 17 with its openings in alinement with the bolts. A cushioning element 29 of wood, lead, or other suitable material is disposed between each end portion of the spreader and a plate 17, against which it is 45 drawn by turning the bolts. One object of the chamber 13 in the tie is to permit insertion and withdrawal of the spreader and cushioning elements thereon.

In a railroad-track having rails mounted 50 in the manner explained on ties formed in accordance with this invention, the rails are maintained in association with the ties with sufficient rigidity to resist torsional efforts imposed by rolling stock passing thereover 55 and to prevent spreading of the rails, and at the same time the opposed cushioning elements 20 and 29 afford such resiliency in the structure as to impart thereto characteristics similar to those of woodied ties.

60 The horses and spreader are associated with other elements in the tie body in such manner that the horses reliably are held in place therein under the stresses of service without imposing such efforts as would be 65 liable to impair the integrity of the struc-

ture, the spreader sustaining much of the stresses that otherwise would be imposed on the body itself and contributing to the maintenance of the rails in proper spaced relation. In view of the fact that the spreader 70 is in the chamber 13 and not embedded in the body, the stresses imposed thereon are not thereby imposed on the body itself.

Having thus described my invention, what I claim as new, and desire to secure by Letters Patent, is—

1. A tie comprising a body, a rail-supporting casing embedded in each end portion thereof having a flat top substantially flush with the top of the body, a longitudinal 80 plate inside of each casing secured to its walls, reinforcing members in said body extending through said casings between their tops and said plates, and means whereby rails are connected with said casings. 85

2. A tie comprising a body, a casing embedded in each end portion thereof, a longitudinal plate secured inside of each casing to its walls, reinforcing members in said body extending through said casings between their tops and said plates, and means whereby rails are connected with said casings. 90

3. A tie comprising a body, a casing embedded in each end portion thereof, a longitudinal plate secured inside of each casing to its walls, reinforcing members in said body extending through said casings on top of said plates, other reinforcing members in said body contacting with the bottom and sides of said casings, and means whereby rails are connected with said casings. 95

4. A tie comprising a body, a rail-supporting casing embedded in each end portion thereof having a flat top substantially flush with the top of the body, a member disposed longitudinally of said body extending into said casings, and rail-securing elements extending downwardly into said casings and connected with said member. 100 105

5. A tie comprising a body, a casing embedded in each end portion thereof, a member disposed longitudinally of said body extending into said casings, and rail-retaining bolts arranged to draw said member against 110 parts of said casings.

6. A tie comprising a body, a casing embedded in each end portion thereof, a member disposed longitudinally of said body extending into said casings and having threaded openings, and rail-retaining bolts having threaded portions disposed in said openings and arranged to draw said member against parts of said casings. 115 120

7. A tie comprising a body, a casing embedded in each end portion thereof, a longitudinal plate inside of each casing secured to its side walls, a member disposed longitudinally of said body extending into said casings below said plates and having thread- 125 130

ed openings, and rail-retaining bolts having threaded portions disposed in said openings and arranged to draw said member against said plates.

5. 8. A tie comprising a body, a casing embedded in each end portion thereof, a longitudinal plate inside of each casing secured to its side walls, a member disposed longitudinally of said body extending into said casings below said plates, and rail-retaining bolts arranged to draw said member against said plates.

10. 9. A tie comprising a body, a casing embedded in each end portion thereof, a member disposed longitudinally of said body extending into said casings, cushioning elements on said member, and rail-retaining bolts arranged to draw said member and cushioning elements against parts of said casings.

15. 10. A tie comprising a body, a casing embedded in each end portion thereof, a member disposed longitudinally of said body extending into said casings and having threaded openings, cushioning elements on said member, and rail-retaining bolts having threaded portions disposed in said openings and arranged to draw said member and cushioning elements against parts of said casings.

20. 11. A tie comprising a body, a casing embedded in each end portion thereof, a longitudinal plate inside of each casing secured to its side walls, a member disposed longitudinally of said body extending into said casings below said plates, cushioning elements interposed between said member and plates, and rail-retaining bolts arranged to draw said member and cushioning elements against said plates.

25. 12. A tie comprising a body, a casing embedded in each end portion thereof, a longitudinal plate inside of each casing secured to its side walls, a member disposed longitudinally of said body extending into said casings below said plates and having threaded openings, cushioning elements interposed between said member and plates, and rail-retaining bolts having threaded portions disposed in said openings and arranged to draw said member and cushioning elements against said plates.

30. 13. A tie comprising a body, a rail-supporting casing embedded in each end portion thereof having a flat top substantially flush with the top of the body, a member disposed longitudinally of said body extending into said casings, and bolts extending downwardly into said casings and arranged to draw said member upwardly toward parts of said casings and rail-retaining elements downwardly toward the tops of said casings.

35. 14. A tie comprising a body, a rail-supporting casing embedded in each end portion thereof having a flat top substantially

flush with the top of the body, a cushioning element on top of each of said casings, a member disposed longitudinally of said body extending into said casings, cushioning elements on said member, and rail-retaining bolts arranged to draw said member and cushioning elements thereon and said top cushioning elements oppositely against interposed parts of the structure.

40. 15. A tie comprising a body having a chamber disposed longitudinally therein, metallic members on top of the body and at the top of the chamber in each end portion of the body, a spreader in said chamber, and rail-retaining bolts arranged to draw said metallic members toward interposed parts of said body.

45. 16. A tie comprising a body having a chamber disposed longitudinally therein, a casing embedded in each end portion thereof having a flat top substantially flush with the top of the body, a longitudinal plate fixed in each of said casings and positioned at the top of said chamber, a spreader in said chamber, and rail-retaining bolts arranged to draw said spreader toward said plate.

50. 17. A tie comprising a body having a chamber disposed longitudinally therein, a casing embedded in each end portion thereof having a flat top substantially flush with the top of the body, a longitudinal plate fixed in each casing and positioned at the top of said chamber, cushioning elements on top of said casings, a spreader in said chamber, cushioning elements between said spreader and plates, and rail-retaining bolts arranged to draw said spreader and cushioning elements thereon and said top cushioning elements against interposed parts of the structure.

55. 18. A tie comprising a body having a chamber disposed longitudinally therein, a casing embedded in each end portion thereof having a flat top substantially flush with the top of the body, cushioning elements on said casings, rail-supporting plates on said cushioning elements, rail-clamps on said plates, a spreader in said chamber, and bolts extending through said clamps, plates, casing tops, and spreader.

60. 19. A tie comprising a body having a chamber disposed longitudinally therein, a casing embedded in each end portion thereof having a flat top substantially flush with the top of the body, cushioning elements on said casings, rail-supporting plates on said cushioning elements, rail-clamps on said plates, a spreader in said chamber, cushioning elements on said spreader, and bolts extending through said clamps, cushioning elements, casing-tops, and spreader.

65. 20. A tie comprising a body having a chamber disposed longitudinally therein, a casing embedded in each end portion there-

of having a flat top substantially flush with the top of the body, a longitudinal plate in each casing positioned at the top of said chamber, cushioning elements on said casings, rail-supporting plates on said cushioning elements, rail-clamps on said plates, a spreader in said chamber, cushioning elements interposed between said spreader and casing-plates, and bolts extending through 10 said clamps into said body and connected with said spreader.

21. A rail-supporting element embedded in a tie comprising a metallic casing having a flat top, and a longitudinal plate se-

cured in and to said casing at a place below 15 its top.

22. A rail-supporting element embedded in a tie comprising a metallic casing having a flat top, and a longitudinal plate in and secured to the sides of said casing. 20

23. A rail-supporting element embedded in a tie comprising a metallic casing having a flat top, and a longitudinal plate having side flanges secured to the sides of 25 said casing.

In testimony whereof I affix my signature.

OLFORD FRANK RUSE.
